SAFETY SWITCH

William Anderson, Bromley, Ky., assignor to The
Trumbull Electric Manufacturing Company,
Plainville, Conn., a corporation of Connecticut

Application February 3, 1936, Serial No. 62,173

2 Claims. (Cl. 200—114)

My invention relates to enclosed switches of an improved type.

One object is to provide a construction in which the line is always dead when the box is open.

5 Another object is to provide a construction in which the cover may be closed either with the contacts in the open circuit or in the closed circuit relation.

Another object is to provide an enclosed type 10 switch in which it is possible to open the cover with safety regardless of whether the circuit is closed or open.

Another object is to provide an enclosed type 15 switch in which the opening of the cover opens the circuit.

Another object is to make a safety switch with a fuse wherein it is impossible to open the casing of the switch without disconnecting the circuit which passes through it.

20 Another object is to increase safety when the casing is opened for inspection of the fuse, switch contacts, or terminal connections.

These and other objects are obtained by mounting the stationary switch contacts, with the fuses, 25 in a receptacle or box with a movable cover. The cover carries a movable switch blade member and means to operate the blade member from outside of the receptacle. When the cover is opened, the blade member, carried by the cover, breaks all 30 connections within the switch.

One embodiment is shown in the drawings, wherein

Fig. 1 is a front view of an enclosed switch embodying my invention.

35 Fig. 2 is a vertical section on the line 2—2 of Fig. 1, the parts being shown in the off position.

Fig. 3 is a vertical section of the device on the line 3—3 of Fig. 2.

40 Fig. 3a is a detail of an insulating guard member.

Fig. 4 is an enlarged plan view of the device of Fig. 1 with the cover removed and parts shown broken away.

Fig. 5 is a bottom plan view of the cover of the 45 receptacle with the parts attached thereto.

Fig. 6 is an enlarged detail view of parts of the mechanism illustrated in Fig. 5, shown in another position.

Fig. 7 is a section taken on the line 7—7 of 50 Fig. 6.

In the drawings a receptacle 10 is provided with a cover 11, hinged at 12 to the receptacle. A hasp 13 may be provided, through which a padlock or seal may be inserted to lock the cover in 55 closed position.

Within the receptacle electrical terminals 14 and 15 are provided, one for connection with a power source or line and the other to the local circuit. Fuses or other protective devices 16 are mounted within the receptacle. Clips or jaws 17 and 18 are provided for electrically connecting the fuses between the terminals 15 and the switch members. Each switch has a pair of separated contacts or jaws 19 and 20. Contact 19 is connected to terminal 14 and contact 20 is connected 10 to a fuse clip 16 through the medium of a connector strip 21.

The terminals, fuse clips, switch jaws and connector strips are mounted upon, although insulated from the receptacle by means of an insulating base 22. This base carries insulating barriers 23 which screen each of the fuse clips 17 and 18 and switch jaws 20 from one another.

The other elements of the switches are mounted on the cover of the receptacle. These include 20 movable switch members with depending blade portions 24 and 25 mounted on an insulating carrier block 26. This block is in turn secured to a slide 27 which is reciprocably mounted between guides 28 on the under surface of the receptacle 25 cover 11.

In the cover 11 is provided an opening 29 through which switch position indicia 30 can be observed. These position indicators ("on" and "off") are attached to the slide 27.

Applied to the under surface of the cover is a disc 31, seated within a circular recess 32 and free to turn therein. A pin 33 is fastened to the under side of the disc 31 and this pin cooperates with a recess or slot 34 provided in the slide 27.

To hold the disc 31 within the recess 32 an upper disc 35 is provided, secured to the lower disc 31 by means of rivets 36. This upper disc carries a handle 37, for moving the switch operating mechanism and also for opening and closing the cover.

A guard member 38 of insulating fibre or other suitable material is mounted to shield the stationary contact jaws 19 and has holes or slots 39 for the passage of the switch blades 24.

With the switch handle and parts in the full line position indicated in Figs. 1, 2, 3, and 6, the switch blade ends 24 and 25 will be spaced from, and out of contact with the switch jaws 19. When it is desired to close the switch the cover must be opened and then the handle 37 may be turned to the position indicated in dot-dash lines in Fig. 2 and in dotted lines in Fig. 5. This turning of the handle moves the pin 33 in an arc and the moving pin, riding in the slot 34, pushes the 50 55 50 55 55

slide 27 to the left, as shown in Fig. 6. This motion of the parts is indicated by the arrows in Fig. 6.

When the slide 27 is in this new position, it has 5 carried with it the insulating block 26 and the attached switch blades so that now the cover may be closed whereupon the switch jaws 19 and 20 will be connected through the blade ends 24 and 25. A reverse turning of the handle will 10 move the parts in the opposite direction when the cover is open.

Now, because of the mounting of the switch blades on the cover of the receptacle, whenever the cover is opened the switch blades are entirely 15 removed from the switch jaws.

The switch member may be moved to and from the open circuit position only when the cover is open.

This structure insures an open circuit whenever 20 the receptacle is opened for inspection, re-fusing or replacement of parts. Furthermore, a single handle, operating both the switch and the cover, serves to reduce the number of necessary parts. The small number of parts in the device as a 25 whole, the form and the arrangement of those few parts, makes for simplicity, durability, efficiency and safety.

The guard member 38 prevents accidental engagement with the contacts when the cover is 30 open and serves to prevent formation of an arc during the opening movement of the switch.

The construction as shown is for use in a three-wire system but the invention is, of course, applicable to single-wire or two-wire lines.

35 I claim:

1. A safety switch including a box having a cover hinged to one edge thereof, a stationary contact mounted in the box and having its main contact surface extending at right angles to the hinged edge of the cover, a slide carried by the 5 cover and slideable in a direction toward and away from the hinged edge, a switch blade carried by said slide and coacting with the stationary contact when the cover is closed, a handle carried by the cover and rotatable about an axis at 10 right angles to the main plane of the cover, said handle projecting from the cover and serving to operate the slide to open the circuit and providing a hand grip for pulling the cover open.

2. A safety switch having a box with a cover 15 hinged at one edge thereof, a slide mounted on the inside of the cover and slideable in a direction toward and away from the hinged edge, a switch blade carried by said slide and having its main contact surfaces extending at right angles 20 to the hinge axis, a projecting handle mounted on the outside of the cover near the edge opposite the hinge edge and connected to said slide and extending parallel to said hinge axis when 25 the switch blade is in the open circuit position, a stationary contact and a stationary fuse connected thereto and mounted in the box body, said blade being adapted to coact with said contact when the cover is closed and the handle extends parallel with the hinge edge, said handle furnishing the means for opening the cover of the 30 box and then moving the switch blade to an open circuit position.

WILLIAM ANDERSON. 35
